UNITED STATES PATENT OFFICE.

GEORGE EVANS, OF PUYALLUP, WASHINGTON.

PLIERS.

1,199,255.

Specification of Letters Patent. Patented Sept. 26, 1916.

Application filed November 2, 1914, Serial No. 869,864. Renewed May 10, 1916. Serial No. 96,713.

To all whom it may concern:

Be it known that I, GEORGE EVANS, a citizen of the United States, residing at Puyallup, in the county of Pierce and State 5 of Washington, have invented certain new and useful Improvements in Pliers, of which the following is a specification, reference being had to the accompanying drawings.

This invention relates to new and useful 10 improvements in pliers and more particularly to gripping pliers, the main object of the present invention being the provision of a pair of pliers which is particularly adapted for use in gripping round headed 15 bolts whereby to securely hold the bolts against rotation, while the nut is being removed therefrom.

Another object of the present invention is the provision of a pair of pliers of the above 20 character which will possess advantages in points of efficiency and durability, is inexpensive to manufacture and, at the same time, is simple in construction and operation.

With the above and other objects in view, 25 the invention consists in the novel features of construction, combination and arrangement of parts as will be hereinafter referred to and more particularly pointed out in the specification and claim.

30 In the accompanying drawing forming a part of this application, Figure 1 is a side elevation of a pair of pliers constructed in accordance with my invention. Fig. 2 is a detail perspective view of one of the gripping jaws; and Fig. 3 is an end elevation of one of the gripping jaws.

In carrying out my invention, I either especially construct a pair of pliers according to my invention, or modify the gripping 40 faces of the jaws of an ordinary pair of pliers.

In the accompanying drawing, a pair of pliers is designated by the numeral 1, which pliers include the handle members 2, each of 45 which is provided with an enlarged portion adjacent the inner ends, one of these enlarged portions being formed with a slot and the other with a bolt extending through the slot, this bolt and slot connection permitting the handles to be shifted upon each other so as to increase or decrease the range 50 of the gripping jaws 4 and 5. Each of the gripping jaws 4 and 5 is cut-away upon its inside face as at 6, so as to leave a relatively 55 sharp blade 7 extending transversely of the

jaws, this blade having an inclined inner face 8 which face is formed with corrugations or teeth 9 which extend parallel with the length of the jaw. It is to be observed that the gripping faces 8 of the jaws are 60 transversely dished or concaved so that they may conform to the curved edge of the bolt head.

The practical use of my invention is illustrated clearly in Fig. 1. The pliers are particularly designed to be used with carriage bolts or other bolts having round heads. In this form of bolt, it is difficult for ordinary pliers to grip the round head of the bolt, so as to hold the bolt firmly, while the nut is 70 being placed on or being removed from the bolt. The jaws of the ordinary pliers merely contact at opposite points with the head of the bolt and do not so engage this pointed head as to hold it from movement. With 75 my device as illustrated in Fig. 3, the corrugated inclined inner faces 8 bite inward and wedge against the periphery of the bolt head, the corrugations biting into the relatively thin periphery of the bolt head and 80 thus holding the bolt head and bolt from any rotational movement. This action occurs whether the pliers be used in connection with a bolt head having a relatively large 85 diameter or in connection with a small bolt head.

It is to be noted that the gripping jaws 7 are slightly concaved upon the inner faces, thus conforming to the peripheral curvature 90 of the bolt head. It is also to be noted that inasmuch as the gripping edges of the jaws are relatively sharp, these gripping edges may be easily inserted between the head of the bolt and the work so as to secure a good purchase upon the bolt head. This is particularly desirable where the bolt head has 95 been drawn snugly up against the work.

While I have shown and described the preferred form of my invention, it will be obvious that various changes in the details of construction and in the proportions may be resorted to for successfully carrying my invention into practice, without sacrificing any of the novel features, or departing from the scope of the invention, as defined by the 100 appended claim.

Having thus described this invention, what I claim is:

A bolt holding tool including a pair of 110 pivotally united gripping jaws, each having

a transversely extending recess in its inner face, said recesses being adapted to receive the convex portion of a bolt head, and serrated gripping faces extending between the recesses and the terminals of the pliers, said faces being transversely concaved whereby they may engage throughout their width with the curved edge of a bolt head the ser-

10 rations being disposed at right angles to the terminal edges of the jaws.

In testimony whereof I hereunto affix my signature in the presence of two witnesses.

GEORGE EVANS.
